VAPOR SEPARATING PUMP AND IMPELLER

Filed July 14, 1945

UNITED STATES PATENT OFFICE

2,422,956

VAPOR SEPARATING PUMP AND IMPELLER

Miles Lowell Edwards, Longview, Wash.

Application July 14, 1945, Serial No. 605,107

11 Claims. (CL. 103—113)

1

This invention relates to devices for separating vapors from liquids, and for pressuring vapor-free liquid.

Specifically, the invention relates to centrifugal pump impellers which separate vapors from liquids, and propel the separated vapors from the pumps so that only fully liquid material is pumped.

A feature of this invention is the provision of a vapor-separating impeller having propeller or screw vanes for inducing axial flow through a pump together with centrifugal vanes for slicing off liquid around the axially flowing liquid to separate vapor therefrom before they centrifugally discharge the liquid.

The pumps of this invention are especially adapted for submersion in ponds of liquid material, and function to pump only fully liquid material from the pond while flowing vapors in the liquid back to the pond. In pumps of this type, it is highly desirable to effect vapor separation before the vapors can be trapped in the pump, so that they can be easily released without appreciable power requirements.

The pumps and impellers of this invention are especially adapted for use in aircraft fuel systems wherein volatile liquid fuel, such as gasoline, breaks up and vaporizes in the tanks of the aircraft as low pressure high altitude conditions are encountered. The invention will hereinafter be specifically described as embodied in a booster pump for an aircraft fuel system, but it should be understood, of course, that the devices of this invention are generally useful for vapor and liquid separating purposes, and for pressuring fully liquid material.

An object of this invention is to provide a pump and motor unit adapted for insertion in a pond of liquid, and having an impeller which simultaneously creates a flow of material through the pump, a separation of the material into its gaseous and liquid components, and a pressuring of the liquid component into a chamber of the pump.

Another object of this invention is to provide an impeller for a liquid and vapor separating pump which has a ring of centrifugal impeller vanes equipped with generally Z-shaped inner ends to create vapor separating chambers therebetween and to scoop material into these chambers.

Another object of this invention is to provide a pump impeller having radially disposed rotating separating chambers, scoops for feeding material into these chambers, and propellers for sweeping vapors out of the upper ends of the chambers.

A still further object of this invention is to provide a vapor and liquid separating pump impeller which has a central axial flow passageway there-

2

through, propellers for inducing upward flow through the passageway, a plurality of elongated vapor-separating chambers of appreciable area around the periphery of said passageway and extending up to the propellers, forwardly projecting vanes for slicing material from said passageway into said chambers, and centrifugal pumping vanes for centrifugally flinging out fully liquid material from the chambers.

10. A specific object of this invention is to provide a pump impeller having a hub, screw vanes extending radially from the hub, a shroud ring surrounding the screw vanes, an outturned flange on the shroud ring, and a ring of impeller vanes depending from the flange and having offset inner legs extending from the screw vanes and projecting radially and forwardly beyond the inner face of the shroud ring.

15. A further specific object of this invention is to provide a pump impeller for vapor separating pumps which has enlarged vapor separating chambers in a liquid flow path through the pump equipped with forwardly projecting walls to direct material into the chambers as the impeller is rotated.

20. A still further object of the invention is to provide a vapor separating pump impeller of increased vapor separating and pumping capacity.

25. Other and further objects of the invention will be apparent to those skilled in the art from the following detailed description of the annexed sheet of drawings which, by way of preferred examples only, illustrate two embodiments of the invention.

30. On the drawings:

Figure 1 is a broken fragmentary vertical cross-sectional view, with parts in elevation, of a vapor separating pump and motor unit according to this invention mounted in a tank and showing the impeller for the pump in section along the line I—I of Figure 2.

35. Figure 2 is an enlarged bottom plan view of the pump impeller for the pump shown in Figure 1.

40. Figure 3 is an enlarged fragmentary horizontal cross-sectional view of a portion of the pump impeller taken along the line III—III of Figure 1.

45. Figure 4 is a view similar to Figure 3 illustrating a modified vane arrangement for the pump impeller.

50. As shown on the drawings:

55. In Figure 1, the reference numeral 10 designates generally a fuel tank having a bottom wall 10a with a large aperture 10b therethrough. The tank 10 represents an airplane fuel tank vented to the ambient air.

60. A mounting ring 11 is mounted on the bottom wall 10a of the tank and surrounds the aperture 10b.

A pump and electric motor unit 12 is submerged in the tank 10. The unit 12 has a base 13 with a peripheral mounting flange 13a thereon underlying the tank wall 10a. Cap screws extend through the flange 13a and are threaded into the mounting ring 11 to secure the base 13 to the tank. A gasket 15 is interposed between the flange 13a and the bottom wall 10a of the tank to seal the aperture 10b.

The mounting base 13 is connected through spaced ribs such as 16 with a pump casing 17 defining an annular volute chamber 18 around and in communication with a central open-ended passageway 19. The volute chamber 18 discharges through a peripheral outlet passageway 20 into an upstanding passageway 21 defined by a tubular boss member 22 which is integral with the base 13 in spaced lateral relation from the casing 17. The tubular boss 22 extends beyond the bottom of the base 13 and receives a conduit fitting 23 in the lower end thereof. A cap 24 closes the top end of the boss, and a single bolt 25 is passed through the fitting 23 and threaded into the cap 24 to clamp the fitting and cap on the opposite ends of the boss. Gaskets 26 are interposed between the ends of the tubular boss 22 and the cap and conduit fitting.

Liquids from the volute chamber are propelled through the passageway 20 into the passageway 21 and thence through the conduit fitting 23 to the fuel line (not shown) of an aircraft fuel system. The fuel line customarily supplies the engine-driven main fuel pump of the system (not shown).

The base 13 has a separate closure plate 27 secured therearound by means of cap screws 28 and maintained in sealed relation with the base by a gasket 29. This closure plate 27 is beneath the outer wall 10a of the tank and provides a sump S for the tank. A drain plug 30 is threaded into the plate 27 and can be removed to drain the sump.

A throat ring 31 is secured to the bottom face of the casing 17 by means of cap screws such as 32. This throat ring 31 defines an inlet I for the pump communicating freely with the sump S. The sump S, in turn, communicates freely with the interior of the tank 10.

The casing 17 has an upstanding leg 33 carrying a base 34 for a motor casing 35. An electric motor in the casing 35 has the drive shaft 36 thereof extending through the base 34 and carrying an impeller 37 for the pump. The impeller 37 has a hub 37a fitting over the lower end of the shaft 36 and held thereon by means of a nut 38. A key 38a fits in complementary slots of the hub 37a and shaft 36 to connect the impeller and shaft for rotation.

A plurality of propellers or screw vanes 37b project radially from the hub 37a and are integral with the hub. Eight vanes are shown, but any number can be used, provided that the same number of centrifugal pumping and vapor separating vanes are used as hereinafter described. These vanes 37b are pitched, to induce an upward flow of material through the passageway 19 of the pump. A shroud ring 37c is secured to the outer peripheries of the vanes 37b. This shroud ring has close-running clearance relationship with the upper end of the passageway 19 and has an outturned flange 37d at the lower end thereof extending into a peripheral gap 39 connecting the passageway 19 with the volute chamber 18. This flange 37d is preferably mounted so as to have close-running clearance

relationship with the wall of the pump casing 17 defining the top end of the gap 39.

A plurality of vanes 40 equal in number to the screw vanes 37b depend from the flange 37d in spaced relation to provide a ring of vanes. The throat ring 31 has a bottom flange portion 31a receiving the lower ends of the vanes 40 in close-running clearance relation thereabove. The throat ring has a diverging side wall 31b extending from the flange 31a to the gap 39. The vanes 40 have outer side edges 40a in close-running clearance relation to the side wall 31b of the throat ring, and have narrow upper and outer end portions 40b extending into the gap 39.

The inner edges 40c of the vanes 40 converge inwardly from the inner end of the flange 31a into the shroud ring 37c and terminate level with the leading lower edges of the screw vanes 37b as best shown in Figure 1.

The vanes 40 provide substantially tangential blade faces 40d beneath the shroud ring flange 37d increasing in width along the diverging edges 40a to extended shallow faces 40e lying in the gap 39. These faces 40d and 40e provide flingers for centrifugal discharge of liquid from the portion 19a of the passage 19 surrounded by the vanes.

The inner portions of the vanes 40a, as best shown in Figures 2 and 3, are offset at 40f to extend substantially radially toward the passage 19a. These radial portions 40f have forwardly projecting inner legs or ends 40g. The forwardly projecting legs 40g cooperate with the radially extending portion 40f to provide, between the inner ends of the vanes, vapor separating chambers C having enlarged areas. Since the inner edges 40c of the vanes converge to lie radially inward of the shroud ring 37c at their upper ends and terminate at the lower edges of the screw vanes in the gaps between the screw vanes, the tops of these chambers are extended to the screw vanes and are uncovered at their inner ends. The extension of the individual chambers into the shroud ring and up to the propeller or screw vanes 37b insures rotational movement of material treated in the chambers up to the point of discharge of the material out of the pump thereby eliminating any dead pockets between the chambers and discharge point.

The contour of the radial portions 40f and forwardly projecting leg portions 40g in the embodiment shown in Figures 1 to 3 is such as to provide scoop-like leading faces 40h in angular relation to the faces 40d of the vanes. The legs 40g have a positive rake or pitch such that inner edges 40c are sharp and are the innermost portions of the vanes. These inner edges 40c should all be equidistant from the axis of rotation of the impeller.

In operation of the pump, liquid, such as gasoline from the tank 10, is strained through a screen 41 surrounding the pump casing to fill the sump S and the entire passageway 19 of the pump. The impeller 37 is thus submerged in liquid. The motor drives the impeller 37 at relatively high speeds to centrifugally discharge liquid from the passage 19a into the volute 18, thence through the passage 20 and into the conduit fitting 23. As the liquid enters the impeller passage 19a, the impeller vanes 40 induce the formation of bubbles in the passage. Liquid in the peripheral portion of this passage is sliced off or scooped up by the legs 40g of the vanes and directed by the leading faces of these inner

ends to form localized circulating pools in the separating chambers C between the scoop-like inner ends of the vanes. These circulating pools or eddy currents of liquid and vapor are held closely adjacent the inner ends of the vanes and extend at their inner ends up to the screw vanes 37b. These screw vanes 37b of the impeller create an upward axial flow of material through the passageway 19 and sweep the vapor-laden liquid in the circulating pools upward and out of the open tops of the pool chambers. The heavier fully liquid material is centrifugally discharged through the channels between the vane faces 40e into the volute chamber 18.

A decided advantage in altitude performance of the pumps was obtained by extending the legs 48g to meet the propeller blades 37b and overhang the gaps between the blades 37b as shown with the number of propeller blades and the number of vanes 40 being equal. This extension of the legs up to the propellers forces rotation of fuel up to the point of discharge back to the fuel tank and allows gas and vapors to flow freely upward under influence of gravity from the centrifugal pumping chambers into the propeller chamber. Thus as failure occurs in a pump, the spaces scribed by the revolving vanes becomes filled with gas bubbles which form gas-filled pockets or cavities acting as a restriction to flow of liquid. Any separation of spaces scribed by the pumping vanes from spaces scribed by the propeller vanes will leave a zone between the two spaces which can become gas bound to impede flow to the propellers and cause early pump failure. The forced rotation of fuel between the pumping vanes and the propeller vanes eliminates gas binding in the zone between the pumping vanes and propellers and actually merges the gas separating chambers to provide extended chambers C.

As shown by the arrows in Figure 3, liquid in the peripheral portion of the passage 19a is sliced off or scooped up by the forwardly projecting legs 40g of the vanes. The lighter bubble-laden liquid is directed by the radial portions 40f of the vanes to form an eddy current in the relatively large chamber C between a pair of vanes while the heavy fully liquid material is thrown outwardly by centrifugal force through a restricted throat T between the vanes. Since the inner end of the chamber C is uncovered, the vapor-rich liquid is discharged out of the pump as explained above. The tangential portions 40d of the vanes 40 act as tangential flingers to throw the heavier fully liquid material through the restricted throat T between the vanes. The centrifugal discharging force of the vanes will, of course, pump liquid into the volute chamber, but before this liquid is pumped, it must pass from a relatively large low velocity separating chamber C through the restricted high velocity throat T. The vane design is such that the lighter vapor-laden liquid and the bubbles of gas and vapor are caused to form an eddy current or recirculating pool within the centrifuge chamber. The inner ends of the vanes keep the bubbles in this chamber until they are discharged upward through rotating channels and, at the same time, the forwardly projecting ends of the scoop-like portions of the vanes continue to slice liquid from the periphery of the passage portion 19a into the separating chambers to increase the pumping capacity of the pump and to prevent the pump from becoming gas-bound in the separating chambers. These scoop-like inner ends of the

vanes feed the separating chambers and the pumping channels between the vanes but, at the same time, hold the bubbles in the separating chambers until they are swept out of the upper ends of the chambers by the screw vanes 37b.

In the modification shown in Figure 4, the impeller 37' having the same screw vanes, shroud ring and shroud ring flange as the impeller 37 is equipped with modified vanes 42 depending from the shroud ring flange 37d. These modified vanes have the same tapered inner and outer edges as the vanes 40 and have the same deep inner vane portions and shallow outer vane portions as the vanes 40. However, the inner ends of the vanes have thickened radially inwardly extending portions 42a with cut-out leading faces 42b forming pockets discharging closer to the inner end of the preceding vane than the scoop-like faces of the vanes 40. Thus, as shown in Figure 4, the radial vane portions 42a have forwardly projecting faces 42c terminating in a re-entrant pocket 42b with the end of this pocket facing the preceding vane close to the inner end of the vane. A vapor-separating chamber C' is thus formed very close to the inner ends of the vanes and is only slightly covered by the shroud ring flange 37d. The recirculating pool or eddy current of vapor-laden fuel is thus kept closer to the inner ends of the vanes. The heavier liquid discharged from the pocket 42b is directed against the tangential face of the preceding vane and must pass through the restricted high velocity throat T' before it can enter the volute chamber.

From the above descriptions it should be understood that this invention provides a vapor and liquid separating pump wherein an axial flow of liquid is induced through the pump, and wherein a centrifugal pumping of fully liquid material free from gas and vapors is obtained. The pumps of this invention have impellers so constructed and arranged as to create recirculating pools or eddy currents of liquid and vapors to release vapor-rich material out of the pump and to prevent vapors and gases from being centrifugally discharged. The vanes of these impellers slice off or scoop up material around the periphery of a pond in the pump to release vapors and gases from the material and to hold the gases and vapors in the path of axial flow through the pump so that they will be swept out of the pump. At the same time the vanes centrifugally discharge the fully liquid material under pressure. The scooping up or slicing off of material from the pond prevents the pump from becoming gas-bound and at the same time increases the pumping capacity of the pump. Pumps equipped with the impellers of this invention have more than twice the pumping capacity of pumps equipped with standard centrifugal impellers.

It will, of course, be understood that various details of construction may be varied through a wide range without departing from the principles of this invention and it is, therefore, not the purpose to limit the patent granted hereon otherwise than necessitated by the scope of the appended claims.

I claim as my invention:

1. A pump comprising a casing having an open-ended fluid flow passage with a communicating pumping chamber therearound, an impeller in said passageway having an axial flow passageway therethrough and a ring of spaced pumping vanes defining channels therebetween discharging into

the pumping chamber, said vanes having offset radially extending inner end portions projecting into said passageway and defining therebetween a plurality of elongated relatively large separating chambers, and forwardly extending legs on said end portions arranged to scoop material in the passageway into said separating chambers.

2. A pump comprising a casing having an open-ended passage therethrough with a communicating pump chamber therearound, an impeller in 10 said passage having spaced propellers for inducing axial flow through the passage, said impeller having a ring of vapor separating and pumping vanes thereon surrounding a central inlet passageway in said open ended passage and providing channels therebetween discharging into the pumping chamber, said vanes having relatively deep inner end portions and relatively shallow outer end portions, and substantially Z-shaped leading ends on said inner end portions of the 15 vanes projecting into said passageway and defining therebetween separating chambers of relatively large area communicating with said channels through restricted throats, said Z-shaped inner ends having legs projecting forwardly to 20 slice off material in said passageway, said legs extending up to the propellers and overhanging the spaces between the propellers, and said Z-shaped inner ends having front faces for directing the sliced off material to create eddy currents in said separating chambers communicating freely with said propellers.

3. A pump impeller comprising a hub, spaced propellers extending radially from said hub, a shroud ring surrounding said propellers, an out-turned flange on said shroud ring, and a plurality of vanes depending from said flange in spaced relation around the flange, said depending vanes having offset inner ends with forwardly projecting legs extending into the shroud ring up to the 40 propellers.

4. A pump impeller comprising circumferentially spaced pumping vanes having open inner ends defining a ring, said vanes extending outward from the ring to define pumping channels therebetween arranged to receive fluids from the space inside of the ring, the inner ends of said vanes extending radially inward and forwardly to provide scoop-like faces extending into the space inside of the ring for defining therebetween 50 relatively large vapor separating chambers.

5. A pump impeller comprising an open ended cylindrical member having an outturned flange at one end thereof, pumping vanes depending from said flange beyond said member, said vanes having inner edges extending inwardly beyond the inner end of the flange and providing scoop-like leading faces disposed outwardly from the axis of the impeller, a hub for said impeller, and screw vanes connecting the cylindrical member and hub arranged to induce axial flow of material to sweep bubbles of gas and vapor from the chambers between the scoop-like faces of the vanes.

6. A pump impeller comprising a ring of circumferentially spaced centrifugal pumping vanes, each of said vanes having a radially inwardly extending inner end portion and a forwardly projecting end on said inner end portion, and said vanes being so constructed and arranged to define therebetween relatively large 65

vapor separating chambers for low velocity recirculation of material together with relatively small pumping channels for high velocity discharge of material, said channels communicating with said chambers through restricted throats.

7. A pump impeller comprising a ring of circumferentially spaced centrifugal pumping vanes having radially inwardly extending thickened portions, the forward faces of said thickened portions having reentrant recesses providing localized scoop-like chambers arranged for eddy current circulation of material sliced off from the space within said ring.

8. A pump impeller comprising a plurality of circumferentially spaced propeller vanes, a ring of centrifugal pumping vanes spaced from the propeller vanes, said pumping vanes being equal in number to the propeller vanes, and forwardly and inwardly projecting legs on the inner ends of the pumping vanes extending to the propeller vanes for defining rotating vapor-separating chambers between the pumping vanes joined with the propeller vanes.

9. A pump impeller comprising a hub, a relatively large number of circumferentially spaced propeller vanes extending radially from said hub, a shroud ring surrounding said propeller vanes and joined thereto, circumferentially spaced centrifugal pumping vanes depending from said shroud ring, said pumping vanes being equal in number to said propeller vanes, and each pumping vane having a radially offset inwardly extending portion with a forwardly projecting leg extending into the shroud ring to terminate level with the lower leading edge of a propeller vane and overhanging the gap between said propeller vane and the next adjacent propeller vane.

10. A pump impeller comprising an annular member supporting a plurality of circumferentially spaced centrifugal pumping vanes therearound, the inner ends of said vanes defining an axial flow passage and the outer ends defining centrifugal pumping channels therebetween, said inner vane ends having portions projecting radially inwardly and forwardly to an increasing degree along said passage in the direction of fluid flow, thereby defining vapor separating chambers between said inner vane ends.

11. A pump impeller comprising an annular member supporting a plurality of circumferentially spaced centrifugal pumping vanes therearound, the inner ends of said vanes defining an axial flow passage and the outer ends defining centrifugal pumping channels therebetween, said inner vane ends having portions projecting radially inwardly and forwardly to define vapor separating chambers between said inner vane ends, and propeller means immediately adjacent one end face of said inner vane ends for producing axial flow of vapor-rich fluid from said chambers.
